UNITED STATES PATENT OFFICE.

JAMES PERCY FISHER, OF MCKENDREE, WEST VIRGINIA.

SELF-WAITING TABLE AND CUPBOARD.

1,160,500.

Specification of Letters Patent. Patented Nov. 16, 1915.

Application filed September 3, 1914. Serial No. 860,114.

To all whom it may concern:

Be it known that I, JAMES P. FISHER, citizen of the United States, residing at McKendree, in the county of Fayette and State of West Virginia, have invented certain new and useful Improvements in Self-Waiting Tables and Cupboards; and I do declare the following to be a full, clear, and exact description of the invention, such as will enable others skilled in the art to which it appertains to make and use the same.

This invention relates to improvements in a combined revolving table and cupboard.

The object of the invention is to provide a simply constructed revolving self-waiting auxiliary table top equipped with removable means for converting it into a cupboard when desired.

Another object is to provide a table having a revolving auxiliary top provided with means capable of performing the double function of handles for operating the auxiliary table top and as securing means for a skirt of screen wire or other protective material.

With these and other objects in view, the invention consists of certain novel features of construction, combination and arrangement of parts as will be more fully described and claimed.

In the accompanying drawings: Figure 1 represents a vertical section of a table constructed in accordance with this invention; Fig. 2 represents a top plan view thereof.

In the embodiment illustrated a pedestal table 1 of ordinary construction is shown having a round fixed top 2 with a bore 3 extending centrally through said top into the pedestal of the table to form a socket for receiving a shaft 4 of a revolving auxiliary top 5. This top 5 is preferably of the same configuration as the fixed top 2, but is smaller than said top 2 to provide sufficient space on said top 2 beyond the edge of the top 5 to adapt it to hold plates and dishes when used for dining. This auxiliary top 5 is shown with its lower face inclined upwardly and outwardly from the center thereof toward its periphery to increase the space between the lower face of said top 5, and the upper face of the fixed top 2 as is shown in Fig. 1. The spindle or

shaft 4 is fixed to the thickened central portion of the auxiliary top 5 and extends into the socket 3, being preferably mounted on ballbearings in said socket. Ballbearings 6 are also preferably arranged between the fixed and revoluble tops at the central portions thereof around the spindle 4, as is shown clearly in Fig. 1.

A protective skirt 7 of screen wire or any other suitable or desired material is removably secured to the periphery of the auxiliary top 5 by means of suitable fastening elements 8, which are preferably provided with heads 9, and also designed to perform the double function of securing means for the skirt and of handles for revolving the table 5. The skirt 7 here shown is constructed of screen wire and the lower edge thereof is disposed in close proximity to the upper surface of the top 2 and is designed to provide a protective covering for converting the table into a cupboard when it is not desired for use as a table. This skirt 7 is here shown projecting at its upper edge above the outer face of the auxiliary top 5 and is designed to form a ledge around the periphery of said top for preventing the sliding off of dishes carried by said top during a revolution thereof.

In the use of this table when it is designed for dining purposes, the skirt 7 is removed by disengaging the fastening elements 8 from the periphery of the top 5 and then reinserting said elements to provide for their use as handles for rotating said top 5 by the diners in a manner ordinary with tables of this character. The inclining of the lower face of the top 5 from its center toward its periphery provides sufficient space between the lower face of said top 5 and the outer face of the fixed top 2 to permit dishes of vegetables and the like to be disposed under the top 5 in a convenient position accessible to the diners. Other dishes are carried by the auxiliary top 5 and are rendered accessible to the different diners by turning said top a partial revolution.

When the meal is over and it is desired to use the table as a cupboard, the articles to be housed are inserted in the space between the two table tops and the protective skirt 7 is then placed in operative position and secured by the fastening elements 8. The

food thus housed under the table top 5 will be protected by said skirt 7 against flies and other insects.

I claim as my invention:

5 The combination with a pedestal table having a fixed top with a central socket extended into said pedestal, of an auxiliary top of smaller diameter having a shank revolvably mounted in said socket, said 10 auxiliary top being spaced from said main top, a skirt of screen wire fabric detachably secured to the periphery of said auxiliary

top with its lower edge arranged adjacent the upper face of the fixed top and its upper edge projected above the face of the 15 auxiliary top to form a retaining ledge.

In testimony whereof I have hereunto set my hand in presence of two subscribing witnesses.

JAMES PERCY FISHER.
